CLAIM

The ornamental design for an illuminated wall socket with switches, as shown and described.

DESCRIPTION

FIG. 1 is a front right perspective view of an illuminated wall socket with switches showing my new design;
 FIG. 2 is a rear left perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.
